CIRCLE MARKER

Anthony J. Goodford, Wilkes-Barre, Pa.

Application August 16, 1950, Serial No. 179,741

3 Claims. (Cl. 33—27)

1

This invention comprises novel and useful improvements in a circle marker and more specifically pertains to circle marker attachments for use with rulers of either the folding or the flexible tape type, for adapting these rulers for use as compasses for scribing circles and arcs of circles of various sizes.

The primary object of this invention is to provide circle marking attachments for use with rulers of either the folding ruler or the steel tape type whereby the ruler may be adapted for use as a compass for scribing or tracing circles or arcs of circles of various sizes with ease and accuracy, and wherein the ruler and the attachments may be compactly folded when not in use.

Yet another object of the invention is to provide circle marking attachments for rulers which may be readily applied to, removed from or adjusted longitudinally of various types of rulers with ease and accuracy.

A still further object of the invention is to provide circle marking attachments for rulers which are specifically adapted for use with conventional forms of flexible steel tape rulers which are yieldingly wound in cup-shaped or cylindrical containers.

And a final important object of the invention is to provide a set of circle marking attachments for rulers which are equally applicable for use with pencils, scribe points, marking chalk and the like for describing circles and arcs of circles of a wide variety of radii.

These, together with various ancillary features and objects of the invention, which will later become apparent as the following description proceeds, are attained by the present invention, preferred embodiments of which have been illustrated, by way of example only, in the accompanying drawings, wherein:

Figure 1 is a fragmentary perspective view showing the manner in which a preferred embodiment of the invention is applied to a flexible steel tape for adapting the same to describe an arc with a pencil employed as a scribe:

Figure 2 is a vertical central longitudinal sectional view taken substantially upon the plane indicated by the section 2—2 of Figure 3 and showing the manner in which the center point clip is adapted to be attached to a flexible steel tape and the housing for the same;

Figure 3 is a vertical transverse sectional view taken substantially upon the plane indicated by the section line 3—3 of Figure 2;

Figure 4 is a vertical longitudinal sectional detail view taken substantially upon the plane in-

2

dicated by the section line 4—4 of Figure 1 and illustrating the manner in which a scribe clip attachment is associated with the end of a flexible steel tape for guidingly receiving a scribe such as a pencil;

Figure 5 is a fragmentary perspective view showing a modified application of the principles of this invention associated with a folding rule; and

10 Figure 6 is a vertical transverse sectional view taken substantially upon the plane indicated by the section line 6—6 of Figure 5.

Reference is now made more particularly to the accompanying drawings, wherein like numerals designate similar parts throughout the various views.

In the following description, it is to be understood that the term "ruler" as used hereinafter and in the appended claims is to be considered 20 as generic to either the flexible steel tape type of ruler or the folding wooden or steel ruler, Figures 1—4 illustrating the invention as applied to a flexible steel tape ruler, while Figures 5 and 6 disclose the application of the invention to a 25 folding wooden or steel rule.

Referring now more particularly to Figure 1, it will be apparent that the invention consists of a center point clip or attachment indicated generally by the numeral 10 and a scribe clip attachment indicated generally by the numeral 12, these attachments being removably and adjustably secured to a flexible steel tape 14 at longitudinally spaced positions along said tape.

As will be readily understood, the flexible steel tape 14 is conveniently of the type which is yieldingly and resiliently coiled in a cylindrical or cup-shaped housing 16, the forward end of this tape having a depending flange or lip 18 in accordance with customary practice.

40 The center point attachment 10, as will be apparent from Figures 1, 2 and 3, consists of a flat sheet metal plate 20 of any suitable thickness, which is provided with a pair of integral upstanding side walls 22 and 24, which are adapted to re-

45 ceive the side edges of the tape 14 and the sides of the tape housing 16 therebetween. As will be readily understood, although sheet metal may be conveniently employed as the material from which the center point clip is constructed, this 50 attachment can likewise be formed of any other suitable material as desired.

A resilient finger 26 in the form of a leaf spring which may be integrally or rigidly attached to one of the side walls as 24, or which if desired may be 55 constructed by striking out a portion of the side

wall to form an integral tongue therewith, is provided for yieldingly biasing the housing 16 and/or the edge of the tape 14 against the other side wall 22. Thus, the tape and/or the housing 16 are resiliently and frictionally held in the attachment 10.

At any convenient point, the bottom surface of the plate 20 is provided with a depending center point 28 which is adapted to be pressed into the surface upon which it is desired to inscribe an arc or circle. The center point 28 may be conveniently formed by striking downward a portion of the plate 20 to provide an integral depending tab beneath the same; or may be formed as a separate point welded or otherwise rigidly secured to the plate 20.

Conveniently, the plate 20 is provided with a further depending member 30 in the form of a flange or the like which may serve to support the attachment 10 as the latter is rotated about the center point 28 to thereby maintain the plate 20 upon a substantially parallel plane to that of the surface upon which the arc or circle is to be inscribed.

At its forward end, the plate 20 extends beyond the side walls 22 and 24, as well as the center point 28 to thus provide a forwardly extending portion 32, which upon one edge of the same may be provided with a V-shaped notch 34 which is substantially in the same transverse plane as the center point 28.

Integrally attached to the forwardly extending portion 32 as by an upstanding flange 36 is a bracket 38 which extends above and overlies in substantially parallel but vertically spaced relation the portion 32. Screw threadedly engaged in a bore through the bracket 38 and in axial alignment with the center point 28 is a clamping member in the form of a thumb screw or the like 40 which thus is adapted to adjustably clamp the tape 14 between the bracket and the plate extension 32 to thus lock the tape in adjusted, extended position.

As so far described and illustrated, the attachment 10 has been applied to a flexible steel tape 14. It will be readily apparent, however, that the same could just as easily be applied to a folding type of rule, whether of wooden or steel construction.

Reference is now made more particularly to Figures 1 and 4 for an understanding of the construction and operation of the scribe clip 12. The latter conveniently comprises a sheet metal bracket having parallel upper and lower plates 42 and 44 which are integrally connected by an upstanding side wall 46, a thumb screw 48 being screw threadedly engaged in one of the plates, such as the upper plate 42 for clamping the forward end of the tape 14 between the two plates. By means of this thumb screw, the scribe bracket is thus adjustably clamped to a portion of the ruler which is spaced from the center point clip 10.

One of the parallel plates of the bracket, such for example as the upper plate 42, is extended forwardly from the other plate and is provided with means for guidingly receiving a scribe. This means may conveniently comprise a suitable guide aperture 50 through which may be extended a scribe such as a pencil 52, the aperture 50 and if desired the forward depending flange 18 of the ruler 14 serving to position and guide the scribe 52 as the latter is rotated through an arc as the device is oscillated or turned about the center point 28 of the center point clip 10.

However, the means for guidingly receiving the scribe further includes a preferably integral, upstanding plate 54 rising from the upper plate 42 in advance of the aperture 50, the outer surface of the plate 54 constituting a seat or shoulder for receiving the side of a scribe such as a pencil, a carpenter's pencil, marking chalk and the like. To facilitate the engagement of the member received and guided by the plate 54, the latter is provided at one side with a vertically and longitudinally disposed projection or flange 56.

The members 54 and 56 thus serve to selectively support alternative scribes as desired; or may cooperate to provide a finger grip when the operator employs a scribe such as that at 52 during the operation of the device.

It will be readily understood that various types of scribes can be employed with this invention, since the pencil 54 could be replaced with a scribing point, a pen, or any other marking or scribing instrument.

The attachments so far described are equally applicable to the flexible steel tape 14 or to a folding type of rule.

However, a further embodiment of the invention of a somewhat simplified construction may be employed which although not limited to the folding type of rule is specifically and efficaciously applicable thereto.

This modification consists of the previously described center point clip 10 together with a modified form of scribe clip, shown in Figures 5 and 6 and indicated generally by the numeral 60. The scribe clip 60 comprises parallel upper and lower plates 62 and 64 which are vertically spaced in substantially parallel relation, and which are integrally joined as by a vertical side flange or plate 66. A thumb screw 68 is screw threaded through the upper plate 62 for clamping a folding rule 70 between these plates. The lower plate 64 is preferably extended laterally beyond the side edge of the upper plate 62 to provide a lateral projection 72 which is notched or recessed as at 74. Conveniently, the bottom plate 64 may be notched or cutaway as at 76 to provide a downturned struck-out portion 78 constituting a depending point.

The attachment 60 may also be substituted for the center point clip 10 by clamping this attachment at any desired position along the rule 70 from the previously described scribe point attachment 12.

From the foregoing it will be apparent that the center point attachment and the scribe attachment of this invention are equally applicable to the folding type or the flexible tape type of rules to adapt the latter for efficaciously describing circles or arcs of any predetermined magnitude.

From the foregoing, it is felt the construction and operation of the invention together with its many advantages will be readily apparent and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A circle marker attachment for rulers comprising a center point clip and a scribe clip adapted for attachment to spaced portions of a ruler, said center point clip comprising an elongated plate having a center point depending therefrom, a pair of side walls rising from said plate for receiving the edges of a ruler therebetween, a bracket mounted on said plate and disposed forwardly of said side walls in spaced overhanging relation upon said plate, a clamping member on said bracket for adjustably securing a ruler between said plate and bracket, a resilient member on one wall for yieldingly biasing a ruler against the other wall, said clamping member being disposed in axial alignment with said center point.

2. A circle marker attachment for rulers comprising a center point clip and a scribe clip adapted for attachment to spaced portions of a ruler, said center point clip comprising an elongated plate having a center point depending therefrom, a pair of side walls rising from said plate and being interconnected with each other solely through the medium of the plate for receiving the edges of a ruler therebetween, a bracket mounted on said plate and disposed forwardly of said side walls in spaced overhanging relation upon said plate, a clamping member on said bracket for adjustably securing a ruler between said plate and bracket, said clamping member being disposed in axial alignment with said center point said scribe clip comprising a bracket having parallel upper and lower plates, a clamping member on said scribe clip bracket for adjustably securing a ruler between said parallel plates, means on said scribe clip bracket for guidingly receiving a scribe in alternate positions, said last means including an aperture in one of said parallel plates for receiving a scribe point, and an upstanding plate on one of said parallel plates and a guide shoulder on said upstanding plate.

3. A circle marker attachment for rulers comprising a center point clip and a scribe clip

adapted for attachment to spaced portions of a ruler, said center point clip comprising a plate having a center point depending therefrom, a pair of side walls rising from said plate for receiving the edges of a ruler therebetween, a bracket mounted on said plate and disposed forwardly of said side walls in spaced overhanging relation upon said plate, a clamping member on said bracket for adjustably securing a ruler between said plate and bracket, said clamping member being disposed in axial alignment with said center point said scribe clip comprising a bracket having parallel upper and lower plates, a clamping member on said scribe clip bracket for adjustably securing a ruler between said parallel plates, means on said scribe clip bracket for guidingly receiving a scribe, said last means including an upstanding plate on one of said parallel plates and a guide shoulder on said upstanding plate.
